UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

SPRING SHACKLE.

Application filed March 16, 1923. Serial No. 625,460.

To all whom it may concern:

Be it known that I, JOHN F. O'CONNOR, a citizen of the United States, residing at Chicago, in the county of Cook and State of Illinois, have invented a certain new and useful Improvement in Spring Shackles, of which the following is a full, clear, concise, and exact description, reference being had to the accompanying drawings, forming a part 10 of this specification.

This invention relates to improvements in spring shackles.

In the operation of mines, it is the custom to employ relatively small mine cars, coupled together by a chain or other simple coupling, without provision for cushioning the shocks under either buff or draft, with the result that the cars are subject to rapid deterioration.

One object of my invention is to provide a very simple, inexpensive, compact shackle bar, suitable for coupling together mine cars in the usual manner and wherein provision is made for cushioning both buff and draft 25 shocks.

More specifically, an object of my invention is to provide a shackle bar of the character above indicated, wherein the two principal parts may be cast from the same pattern, to thereby reduce the cost of manufacture.

The invention furthermore consists in the improvement in the parts and devices and novel combinations thereof, as more fully 35 pointed out in the claims hereinafter.

In the drawing forming a part of this specification, Figure 1 is a side elevational view of portions of two mine cars showing my improvements in connection therewith. Figure 2 is an end elevational view of the shackle bar shown in Figure 1, the view in Figure 2 being turned, however, through an angle of 45° as compared with the position occupied by the shackle bar on the cars. Figure 3 is a longitudinal sectional view corresponding to the section line 3—3 of Figure 2. Figure 4 is a vertical, transverse, sectional view corresponding to the line 4—4 of Figure 3. Figure 5 is a side elevation of one 50 of the members of the shackle bar as said member appears in side elevation in the position shown in Figure 3. And Figure 6 is an end elevational view of one of the 55 spring followers.

In said drawing, the two mine cars are

indicated broadly by the reference character A, each of said cars being suitably mounted on wheels and provided with heavy floor boards 10. In the arrangement shown, each car is provided with an end buffer plate 11 and a coupling bar 12 spaced upwardly therefrom, said plate and bar being provided with vertically aligned openings to receive a coupling pin 13.

The improved shackle bar, as shown, comprises two like castings B and B', a spring resistance C; two followers D and D'; and two spring washers E and E'.

The two castings B and B' are of like construction and made from the same pattern to reduce cost of manufacture. Each of said members, particular reference being had to the member B, as shown in Figures 3, 4 and 5, is provided at one end with a heavy ear 14 having an opening 15 therethrough to accommodate the coupling pin 13, it being understood that, when the parts are in position the heavy ears 14 will extend in horizontal planes in alinement with each other as shown in Figure 1. Each of said members B is also provided with a pair of longitudinally, extending, diametrically disposed arms 16—16, each of arcuate cross section and extending through an arc of 90°. Where the arms 16 join with the heavy 75 ear 14, the casting is provided with a vertically arranged end wall 17 of substantially circular form, as best indicated in Figure 2, the same departing from a true circular 80 form by reason of two arcuate notches or recesses 18—18 placed therein at diametrically disposed points to accommodate the ends of the opposite member B or B' as the case may be. As will be clear from an 85 inspection of Figure 2, a line joining the centers of the notches 18 will extend through the heavy ear 14 at an angle of 45° with the latter. Inwardly of the end wall 17, the arms 16 are provided with transverse 90 shoulders 19—19, and a longitudinally extending groove or guideway 20 is left between the arms, as indicated best in Figure 3 at the lefthand end thereof. The ends of said recesses 20 may be curved as indicated at 95 21 to accommodate the rounded bosses on the corresponding followers D and D' when the shackle bar is under full compression.

The two members B and B' are angularly offset with respect to each other 90° so that the two arms of the one will slide between 100 105 110

the two arms of the other and together all four arms will complete a substantially cylindrical housing or casing within which is received the spring C, as best illustrated in Figure 4, and in this connection, it will be noted that by the arrangement so far described, the two attaching ears 14 are left in the same horizontal plane while the two parts B and B' are made from the same pattern.

Each of the spring followers D and D' comprises two sector-like ends 22—22 united by an intermediate section 23, the arc of each section-like end 22 being 90° so as to leave two diametrically disposed openings 24—24 to accommodate the arms of the corresponding member B or B'. Each follower D is formed with an opening 25 extending therethrough within which is received a heavy rivet 26, the latter rigidly uniting the follower D or D', with the corresponding member B or B', as clearly illustrated in Figure 3, at the outer or free ends of the arms 16. The parts will be so arranged that the inner flat faces of the followers D and D' will be flush with the corresponding shoulders 19 when the parts are in normal position.

The spring washers E and E' are of like construction each comprising a flat plate from which is extended an integral stud 28, centrally disposed, the studs 28 serving to center the two coil spring resistance C and also being so proportioned that they serve as limiting stops to determine the compression stroke of the shackle bar.

As clearly shown in Figure 3, clearance is left between the respective followers D and D' and the ends of the recesses within which they move, to allow for the desired compression stroke of the shackle bar.

In operation, assuming a draft action and the member B' held stationary, the member B will be pulled toward the left as viewed in Figure 3, thereby moving the follower D with it and compressing the spring C against the washer E', which is held by the follower D', in turn rigidly associated with the member B'. In a buffing action, assuming the member B' held stationary, the member B can move toward the right as viewed in Figure 3, thereby carrying the washer E' with it and compressing the spring against the other washer E which, in turn, is held fixed against the shoulders 19 of the member B'.

From the preceding description, it will be seen that the shackle bar which I have designed is unusually compact, the spring is well housed and thus protected from injury, and the parts are of such construction that they may be cheaply manufactured and assembled. Furthermore, the shackle is of such design that it may be coupled with the cars in a simple, well-known manner.

I have herein shown and described what

I now consider the preferred manner of carrying out the invention, but the same is merely illustrative and I contemplate all changes and modifications that come within the scope of the claims appended hereto. 70

I claim:

1. In a resilient shackle, the combination of two oppositely arranged yoke members, each having an extension by which it is adapted to be connected to a vehicle, each 75 said member having abutment shoulders at one end and a rigidly associated follower at the other end, the two members being angularly offset 90°; of a pair of washers within said members, each normally in engagement with the abutment shoulders of one of said members and operable by the follower of the other of said members; and cushioning means between said washers.

2. In a resilient shackle, the combination 80 with two oppositely arranged yoke members each having a flange extension at one end thereof, said flanges extending in the same plane and each adapted to be connected to a vehicle, said members having each abutment 85 shoulders at one end and a rigidly associated follower at its other end, and the two members being angularly offset 90°; of a pair of washers within said members, each normally in engagement with the abutment shoulders 90 of one of said members and operable by the follower of the other of said members; and cushioning means between said washers.

3. In a resilient shackle, the combination 95 with two oppositely arranged yoke members 100 each having a flange extension at one end thereof, said flanges extending in the same plane and each adapted to be connected to a vehicle, said members having each abutment shoulders at one end and a rigidly associated 105 follower at its other, and the two members being angularly offset 90°, said members being in the form of castings and of like construction throughout; of a pair of washers within said members, each normally in engagement with the abutment shoulders of one of said members and operable by the follower of the other of said members; and cushioning means between said washers.

4. In a resilient shackle, the combination 110 with two linked members and cushioning means therebetween, each of said members having parallelly arranged, diametrically disposed flanges of arcuate cross section, the flanges of one being angularly offset 90° 115 from those of the other and slide longitudinally relatively to each other, said flanges when the members are assembled, forming a substantially cylindrical casing within which the cushioning means is housed; of means for detachably attaching each of said members to a vehicle.

5. In a resilient shackle, the combination 120 with two like castings, each having a flange 125 at one end and a pair of diametrically dis-

posed, spaced arms of arcuate cross section, the two members being angularly offset 90° and with the arms slidable upon each other; of a follower rigid with the ends of each pair of arms; a washer normally in engagement with each of said followers; and cushioning means between the washers.

6. A resilient shackle, including in combination, spaced members provided with oppositely disposed cooperating arms; a follower secured adjacent the ends of each set of arms; and cushioning means disposed within said arms and operated upon by said followers, said arms being arranged to provide a closed housing.

7. A resilient shackle, including in combination, spaced members provided with oppositely disposed cooperating arms, each set of arms being arranged to slidably extend outside of its related member; followers secured adjacent the ends of each set of arms, one of said members having an abutment for cushioning means and a recess permitting movement of the follower associated with

the other of said members past said abutment; and cushioning means associated with said arms and operated upon by said abutment and followers upon actuation of said shackle in opposite directions.

8. A resilient shackle, including in combination, spaced members provided with oppositely disposed cooperating arms each set of arms being arranged to slidably extend outside of its related member, one of said members being provided with an abutment and a recess; of a follower secured adjacent the ends of each set of arms one of said followers being movable past said abutment into said recess, cushioning means disposed within said arms and operated upon by said members and said followers to compress said cushioning means in buff and draft; and connecting ears formed on said members and disposed in a common plane.

In witness that I claim the foregoing I have hereunto subscribed my name this 14th day of March, 1923.

JOHN F. O'CONNOR.
